METHOD OF MAKING FLEXIBLE SHAFTING

Original Filed April 13, 1928 3 Sheets-Sheet 3

UNITED STATES PATENT OFFICE

LOUIS H. MORIN, OF NEW YORK, N. Y.

METHOD OF MAKING FLEXIBLE SHAFTING

Original application filed April 13, 1928, Serial No. 269,719. Divided and this application filed November 13, 1928. Serial No. 319,106.

This invention relates to the manufacture of flexible shafting such as is commonly used to transmit torque along a tortuous path and is a division of my copending application 5 Serial No. 269,719, filed April 13, 1928.

Flexible shafting of this type is generally composed of a core wire surrounded by laminations of wire wound around the core wire, the successive layers generally being wound 10 in relatively reversed directions. Heretofore the shafting was usually made by devices which coiled the wire in layers around the core wire as the core wire was pulled along by some independent means or as the coiling 15 device was moved axially along the core wire. Other machines gave a twist to the core wire as it was pulled along by some independent means. In devices of this nature, where independent means were used for 20 causing relative lineal movement between the core wire and the layer wire, it is extremely difficult to properly coordinate the lineal feeding movement relatively to the wrapping movement due to variations in 25 wire size and other conditions often resulting in an unevenly wound product.

It is the purpose of my invention to provide a method whereby the feeding action is accurately controlled and automatically 30 compensates for any variations in wire size. In accordance with my method, the very winding operation or the laying of the convolutions of layer wire upon the core wire produces a feeding action which may be said 35 to be inherent in the winding or manufacture of shafting, i. e., the winding of the layer wire upon the core develops a propelling action of the core in a lineal direction, thus eliminating the necessity of a separate 40 feeding element and its coordination with the other elements of the machine necessary. In carrying out my method, I make use of the well known principle of the wedge and one of its applications.

45 In the making of flexible shafting and in analogous arts which employ the step of automatically winding strand material upon a traveling core, it has been customary to cause longitudinal movement of the article 50 as fast as it is formed by means of a wedg-

ing action. In other words, the strand or strands of material in their passage from the spools to the axis about which they are wound, encounter an inclined surface which develops a propelling force in the strand 55 longitudinally of the axis of the finished product.

With single head machines it is a very simple matter to apply this principle in the production of flexible shafting formed by 60 the winding of successive layers of wire about a core wire. Difficulty, however, arises in applying this principle to multiple head machines. It has been found that it is necessary to provide for a certain automatic 65 compensation between the several heads. This is due to several causes. The core wire passes in succession through the several heads and has the layers of wire wound successively on it. It is necessary that the core 70 wire shall be kept comparatively taut and moving at a constant rate of speed and that there be no open spaces between the convolutions of the wires of the several layers but that the convolutions be closely compacted. 75

Theoretically, it is possible to so relate the speed of rotation of the several heads that with a given size of wires they will wind their respective layers with nice precision. Practically, however, this is not possible. The chief difficulty arises from variations in the size of the wire from the size at which it is rated. A wire which was rated at a certain gauge will almost inevitably 80 vary as much as one-half thousandth above and below that size from the beginning to the end of the wire. This constant variation in the wire size has to be compensated for without interfering with the propelling 85 function of the inclined surfaces.

I have found that this is very satisfactorily done if the inclined surfaces are so shaped that the wires may take a turn or two about them at the initiation of the 90 operation and increase or decrease this surplus or spare wire between the spool and core as the diameter of the wire varies throughout a single spool.

In accordance with my invention I make 100

the inclined surface conical in shape. A retarding force is applied to the spool so that the wire is tightly drawn around the cone and the angle of the cone is such that the downward component of the force considerably exceeds the component normal to the surface. I have not been able to use satisfactorily a cone having an angle of less than 45° and I prefer an angle of not less than 60° .

10 The gear ratio for each head is properly selected according to the size of the wire of the spools on that head. The wires will be given at least a partial turn around the cone.

15 If the diameters of the wires on the several spools of the head do not vary throughout their length, there will be no variation in the extent of the wire turned about the cone. If, however, the size of one or more of the 20 strands temporarily increases, the wire will automatically build up on the cone; and similarly, if the size of one or more of the wires decreases temporarily, the wire will automatically be gradually fed off from the cone until normal conditions are resumed.

25 Without some such compensation or differential action I have found it impossible satisfactorily to use the multiple head machine in the production of flexible shafting.

30 Preferably, there will be provided after the last head a friction device through which the shafting is fed and which will provide a force opposing the propelling force of the cones and thereby cause the turns of the 35 several layers to be closely wound. This opposing or retarding force will be adjustable to accommodate it to the conditions desired.

30 Likewise, I find it advantageous, though not necessary, to employ an auxiliary feeding device after the friction member just mentioned so as to relieve the cones of the necessity of performing all the propelling action and at the same time maintain the 45 finished shaft taut between the last head and the auxiliary feeding device. Thereafter the shafting may be reeled or otherwise disposed of.

As one form of machine for carrying out 50 my method, I have devised the following machine which forms the subject matter of my copending application above referred to and which will be described here to illustrate more clearly my method.

55 In the drawings:

Fig. 1 is a plan view of a machine constructed in accordance with this invention;

Fig. 2 is a front elevation of the same;

Fig. 3 is an enlarged section showing the 60 details of portions of the last winding head and associate parts;

Fig. 3^a is a detail section of the upper end of the retarding device;

Fig. 4, vertical section of one of the rotary 65 winding heads;

Fig. 5 is an end elevation of one of the winding heads.

The machine illustrated comprises a bed or frame 1 supported upon end and central legs 2, the bed 1 constituting a support for the core wire spool, the wrapping or winding mechanism and the flexing mechanism. A spool 3 of core wire 4 is supported upon angle bracket 5 rigidly secured to the bed 1 adjacent the right or head end thereof, the bracket 5 serving to support a suitable spindle and retaining means for rotatably carrying the spool of core wire. Four similar winding heads 6 through which the core wire is passed to have a plurality of layers of wire wrapped therearound are rigidly secured to the bed in alignment. Following the last head 6 there is a flexing head 7 and an auxiliary feed device 43 both also rigidly secured to the bed 1 coaxially with the other heads. The winding heads, flexer, and auxiliary feeding device are all rotated from a common shaft 8 through cross shafts 8^a and suitable gearing adapted to drive successive heads in relatively reversed directions and also adapted to be adjusted to vary the driving speed as described in greater detail in my copending application referred to. The shaft 8 may be driven by a belt 9 passing over a pulley 10 which may be clutched and declutched to the shaft 8 through a suitable clutch 11, the belt 9 being driven from any suitable source of power. The clutch may conveniently be controlled from any point along the length of the machine by means of a rod 12 extending the full length of the machine and connected to the clutch through a lever 13 pivoted to the frame at 14.

Within each of the winding heads or turrets 6^a shaft 15 is rotatably supported on 105 suitable taper bearings 16. The end of the shaft is formed with a flange 17 to which is riveted or otherwise secured a disc or plate 19. A second annular disc 20 of substantially the same diameter is secured to disc 19 in parallel spaced relationship thereto by means of spacing ferrules 21. Spools of wire 22 which supply the layer wire to be wrapped around the core wire are rotatably supported between the two discs 19 and 20 110 upon spindles 23 mounted upon ball bearings 24. In the illustrated embodiment 5 such spools are shown upon each head but it is obvious that any desired number of spools may be employed. The outer disc 20 has 5 hollow bosses 25 arranged around its periphery in such positions as to lie adjacent the outer flanges of the five spools. Within 115 these bosses there is positioned cup-like friction elements 26, constantly urged against the spool flanges by compression springs 27, thus retarding rotation of the spools. At the center of the inner flange 19 there is secured thereto a wire feeding and guiding device 28 having a central bore through 120

which the core wire passes and having one end of its outer surface smooth and tapered as at 28^a, that is having the shape of a truncated cone with its small end of such a 5 diameter as to exactly surround the core wire or the core wire with its previous layer or layers thereon. The inclined surface is smooth and preferably very hard for means which will appear hereafter. A keeper 30 is 10 supported upon 4 studs 31 threaded into flange 17, the keeper having a central bore through which the core wire passes, a portion of the inner surface of which is inclined outwardly at an angle complementary to the 15 inclined surface 28^a of the outer portion of member 28. The keeper 30 is resiliently urged into contact with the feeding and guiding device 28 by means of springs 32 surrounding the outer ends of studs 31 the 20 tension of the springs being variable by adjusting the nuts on the studs.

Between the output side of the last winding head 6 and the rotary flexing head 7 which may be of any type and is illustrated 25 as being like that disclosed in my co-pending application Serial No. 209,205, there is provided a friction block or retarding device 35 comprising a standard the upper end of which is formed into a pair of viselike gripping 30 jaws 36 and 37 pivotally connected together at 38 and resiliently urged together by spring 39 surrounding an eyebolt 40 and being held under tension by means of a wing nut 41.

35 Under certain conditions it may be desirable to provide an auxiliary feeding device although the same is not necessary for the normal operation of the machine. In such instances a gripper or feeding unit may be 40 employed and secured to the bed of the machine at the discharge end of the flexing head 7 or between the last winding head 6 and the flexing head 7. In the illustrated embodiment I have shown a feeding unit 45 43 secured to a bracket 44 attached to the end of bed 1. The feeding device shown comprises a head having 3 ball chucks for gripping the wire, each of the chucks being moved longitudinally at alternate times with 50 overlapping strokes to continuously feed the core wire with its surrounding layers in a steady continuous manner. Such a feeding device is shown and described in my copending application Serial #209,205 and will 55 not be described in detail here since any continuous feeding device may be utilized and driven from the common shaft 8 through a cross shaft 8—A.

The operation of the machine is as follows: The core wire is led off the spool 3 and inserted through the first head 6. The wires from the spools 22 of the first head 6 are then led from the spools and attached to the core wire after which the first head is 65 rotated in a given direction. As the first

head is rotated to lay the wires of the spools 22 thereon around the core wire in close convolutions to form the first layer thereon, the wires take a partial turn around the conical surface of the guiding and feeding member 28. These wires have a tendency to slide down this inclined smooth surface under the keeper 30 which tendency is increased by the friction devices 26 retarding the unwinding of spools 22. This tendency of the layer 70 wires to slide down the inclined surface of member 28 and to crowd in between the last convolution wound and the end of the member 28 urges the core wire with the first layer thereon longitudinally toward the next 75 head or layer. The movement of the wires down the inclined surface is restricted by the keeper 30 which also causes the layer wire to strike the conical surface at a given point and to take a course down the surface 80 of the conical surface rather than parallel thereto transverse to the elements is resiliently urged against the inclined surface and thus prevents the various wires from the 85 spools 22 from crossing or from piling one 90 upon the other as they are wrapped around the core and tends to aid in the feeding of the core wire. The keeper also guides the 95 layer wires to a given point on the conical surface regardless of the point at which it leaves the spool. As the core wire traverses through each head the action is the same, it being understood of course that each head is designed to lay a separate layer on top of the previous layer and wound in a direction 100 reversed relatively to the preceding layer. As the core wire with four layers thereon emerges from the last winding head 6 it is passed through the retarding device 35 which frictionally engages the shaft to hold 105 against the inherent feeding action of the four previous heads constituting a resistance against the inherent feeding action and thus causing the convolutions of wires forming the layers to be closely wound, that is it prevents the feeding action from going too fast and resulting in a loosely wound shafting. Leaving this device the flexible shaft is passed through a rotary flexer 7 which serves 110 to flex the finished cable to make it limber and pliable. Emerging from the flexer the shafting is engaged by the auxiliary feeding device, if such is employed, from which the shafting may be wound on reels or any other suitable container for holding the shafting.

115 It is obvious that various changes may be made in the details of structure without departing from the spirit and scope of this invention as defined in the appended claims.

Claims:

120 1. The method of making flexible shafting having a core wire and a plurality of layers of wire successively wound thereon consisting in passing the core through the axes of a plurality of cones having an apex 125 130

angle of at least 45° and disposed in succession and rotating a wire strand about the axis of each cone and thereby winding it about the core and simultaneously pulling it obliquely about the conical surface and utilizing the downward components of the force of the wires thus created to advance the core through the cones.

2. The method of making flexible shafting having a core wire and a plurality of layers of wire successively wound thereon consisting in passing the core through the axes of a plurality of cones having an apex angle of at least 45° and disposed in succession and rotating a plurality of wire strands about the axis of each core thereby winding them as a band about the core and presenting them individually to the conical surface at different circumferential points and winding them obliquely more or less about the conical surface before reaching the core and simultaneously pulling them in the direction of their obliquity around the conical surface and thus creating a force in the wires having a component downward of the conical surfaces sufficient to propel the core continuously through the cones, and continuously taking up the finished shafting as it is thus advanced by the cones.

30 In witness whereof, I hereunto subscribe my signature.
